The ornamental design for a pool cleaner body, as shown and described.

DESCRIPTION

FIG. 1 is a top, right, rear perspective view of a pool cleaner body showing our new design;

FIG. 2 is a top, right, front perspective view thereof;

FIG. 3 is a bottom, left, front perspective view thereof;

FIG. 4 is a bottom, left, rear perspective view thereof;

FIG. 5 is a right side view thereof;

FIG. 6 is a left side view thereof;

FIG. 7 is a front view thereof;

FIG. 8 is a rear view thereof;

FIG. 9 is a top view thereof; and,

FIG. 10 is a bottom view thereof.

The broken lines in the figures illustrate portions of the pool cleaner body that form no part of the claimed design.

1 Claim, 10 Drawing Sheets(56)
